UNITED STATES PATENT OFFICE.

HOWE E. DANTZEBECHER, OF PHILADELPHIA, PENNSYLVANIA, ASSIGNEE OF ONE-HALF TO GEORGE A. GUMPHERT, OF VENTNOR, ATLANTIC CITY, NEW JERSEY.

DISHWASHER.

Application filed January 12, 1921. Serial No. 436,631.

To all whom it may concern:

Be it known that I, Howe E. Dantzebecher, a citizen of the United States, residing in the city and county of Philadelphia, 5 State of Pennsylvania, have invented a new and useful Dishwasher, of which the following is a specification.

My invention consists of a novel construction of a dish washer, wherein I employ a 10 tank or casing having therein a vertical conduit or stand pipe, having located at its lower portion one or more propeller wheels, or water propelling devices and at its upper portion, a freely revoluble, rotary water 15 sprayer or spreader having pockets on its under surface of novel construction, against which the water discharged from the stand pipe impinges, said stand pipe being provided with a series of upper and lower ports 20 or inclined slots, which in conjunction with the rotary spreading or spraying device, serve to discharge the water or cleaning fluid laterally at different angles and forcibly upon the articles to be washed, which are 25 supported upon racks, screens or baskets, in the upper and lower portions of the body or casing of the device.

It further consists of a novel manner of constructing the wheel pit or sump of the 30 dish washer and in the provision of novel means for supporting the vertical conduit or stand pipe.

It further consists of novel means for supporting, packing and guiding the driving 35 shaft in the lower portion of the apparatus whereby said shaft is packed, guided and supported in an effective and reliable manner.

It further consists of a novel construction 40 of a sump or wheel pit member adapted to be secured to the bottom of the casing or tank and provided with novel supporting means for the vertical conduit or stand pipe, which latter is adapted to be readily assembled or disconnected according to requirements, the construction being such that the 45 inlet of fresh water or cleansing fluid is some distance below the top or water level thereof, upon which the scum or grease will float, whereby a continuous supply of clean water 50 can be used over and over again in the washing operation.

It further consists of a novel construction 55 of a vertical conduit or stand pipe having ports in its intermediate and upper por-

tions in conjunction with a novel construction of a rotary water sprayer or spreader adapted to eject the water forcibly in different lateral or inclined planes or lines upon the articles to be washed.

It further consists of a novel construction 60 of a sprayer or spreader, which is automatic in its operation, being continuously rotated by the impact of the water against the pockets in the bottom surface of said sprayer, 65 there being a plurality of said pockets of novel construction, whereby the water is forcibly deflected in a number of different planes against the articles to be cleaned.

It further consists of other novel features 70 of construction and advantage, all as will be hereinafter fully set forth.

For the purpose of illustrating my invention, I have shown in the accompanying drawings forms thereof which are at present 75 preferred by me, since they will give in practice satisfactory and reliable results, although it is to be understood that the various instrumentalities of which my invention consists can be variously arranged and organized 80 and that my invention is not limited to the precise arrangement and organization of these instrumentalities as herein shown and described.

Figure 1 represents a vertical sectional 85 view of a dish-washer embodying my invention, certain of the parts being shown in elevation.

Figure 2 represents a plan view of Figure 1, with the cover removed, showing the 90 upper end of the vertical conduit or stand pipe and the upper screen, rack or basket upon which the smaller articles to be washed may be supported.

Figure 3 represents a section on line 3—3 95 of Figure 1 showing the lower supporting screen, rack or basket and the tangentially arranged ribs thereon.

Figure 4 represents a plan view of the sump or wheel pit member in detached position, upon which the vertical conduit or 100 stand pipe is supported.

Figure 5 represents a detailed, fragmentary section on line 5—5 of Figure 4.

Figure 6 represents a side elevation of 105 the lower end of the conduit or stand pipe, showing the bayonet joint therein.

Figure 7 represents a plan view of the top of the rotary sprayer or spreader in detached position.

Figure 8 represents a plan view of the bottom or under side of the sprayer or spreader seen in Figure 7.

Figures 9, 10 and 11 represent side elevations of Figure 7, viewed from different angles.

Figure 12 represents a section on line 12-12 of Figure 7.

Similar numerals of reference indicate corresponding parts.

Referring to the drawings:—

1 designates my novel construction of dish washer, the same comprising a tank or casting 2, having the bottom wall 3, whose inner periphery 4 is secured to or supported on the ledge 5 of the casting, sump or wheel pit member 6, which is provided with the drain pipe 7 having the valve or cock therein. The central bottom portion of the sump or wheel pit member 6 is provided with the vertical bearings 9, in which is mounted the propeller shaft 10, which passes through the stuffing box 11, the lower end of said shaft having the coupling 12, which is attached to the coupling 13 of the motor shaft 14, which is driven by the electric motor 15 of any desired or conventional type. The motor is supported by means of the brackets 16, whose upper ends are bolted or otherwise secured to the outer portion of the sump or wheel pit member 6.

The upper end of the driving shaft 10 is provided with a suitable thrust bearing 16, and terminates in the propeller shaft 17, which carries the upper and lower propellers 18 and 19, which rotate and are contained in the vertical conduit or stand pipe 20, whose lower end is supported upon the seats or shoulders 21 of the upward extensions 22 which are preferably cast integrally with the sump or wheel pit member 6.

Below the propellers, I locate the umbrella shaped deflector 37, thereby forming the bottom sediment chamber 38, which receives the heavier particles or impurities.

About the middle of the conduit 20, I locate the ports 23, which are adapted to direct the water or other cleansing agent upon the lower articles, as plates, or the like 24, which are supported on the lower rack, screen or basket 25, and in the upper portion of said conduit, I locate the ports 25, which are adapted to direct the water upon the smaller articles as cups 26 or tumblers 27, which are supported upon the upper rack, screen or basket 28.

In the upper portion of the conduit 20, I locate the bar or spider 29, on or in which is supported the lower end of post 39 on the upper end of which is loosely mounted the rotary water sprayer or spreader 30, which is retained in position by the wing nut or the like 31, the lower surface of the rotary sprayer being slightly above the top of the conduit 20, and having its bottom composed

of a plurality of pockets as three or more of novel construction, whose function is to forcibly discharge the water downwardly in different planes upon the articles to be washed, it being understood that said sprayer is continuously rotated by the force of the water impinging on its under side, which is discharged or propelled upwardly through said conduit or stand pipe.

The racks, screens, or baskets 25 and 28 are supported within the casing 2 by any convenient means as the lugs 32 and 33 and upon the upper surface of the lower rack, screen or basket 25, I preferably provide a series of curved or tangential ribs as 34 against or upon which the lower edges of the plate or the like 24 may be supported, said ribs having the function of splashing or deflecting the streams of water impinging thereon, it being evident that the upper rack or basket 28 may also be supplied with such ribs.

The lower end of the vertical stand pipe 20 may be supported on the posts 22 in any suitable manner, but I preferably provide the same with angular slots 35, which are adapted to engage the pins 36, so that on dropping the stand pipe in position and giving it a slight rotation, the slots 35 in the lower portion thereof will interlock with said pins 36.

I desire to call special attention to the construction of the plurality of pockets on the underside of the rotary water sprayer or spreader 30, reference being had to Figures 7 to 11, which will now be described in detail.

The rotary water sprayer or spreader 30 revolves freely on the upper end of the post 39, which passes through the hub member 40 of said sprayer. The bottom surface of the sprayer is normally slightly above the top of the stand pipe 20, as will be understood from Figure 1, and its bottom is constructed with the plurality of pockets 41, 42 and 43 of successively decreasing depth and whose top walls as 44, 45 and 46 are each of slightly different contour, as will be understood from Figures 9, 10 and 11. The deepest pocket 41, see Figure 9, has the abutment or wall 47, and its upper edge 48 is cut away or is a slight distance from the bottom of the sprayer, so that the water can emerge from the pocket 41 in a lateral direction in a whirling manner. The pocket 42 has the abutment or wall 49, as will be understood from Figures 10 and 8, and its top portion is of slightly different contour from the top of the pocket 41, as is evident.

The pocket 43 has the abutment or wall 50 and its top wall 46 is slightly concave, as will be understood from Figure 11.

It will be seen from the foregoing that the three pockets 41, 42, and 43 are all of slightly different contour, so that the water which is discharged against them upwardly through the stand pipe 20 emerges laterally, 130

is given not only a spiral or whirling action but is continuously discharged in different planes, it being apparent that the spreader rotates automatically due to the upward pressure of the water column in the stand pipe 20.

The operation is as follows:—

The cover 51 having been removed, it will be apparent that the plates or similar shallow articles can be supported upon the lower basket 25 in an inclined direction, as will be understood from Figure 1, the screen 28 being removed so as to enable the plates or the like 24 to be placed in position. The screen 28 is then placed in position and the smaller articles to be washed, such as cups and tumblers 26 and 27 having been placed upon the screen 28 and the motor 15 being started, it will be apparent that the action of the propeller or double propellers 18 and 19 will be to force a constant current of water upwardly through the stand pipe against the under side of the rotary spreader 30.

The rotary spreader 30 is automatically rotated and not only discharges the water in a whirling or spiral direction laterally and downwardly upon the articles to be washed, but in addition, such articles are subjected to the action of the streams which issue through the ports 23 and 25 whereby all the articles are effectively washed.

It will be apparent that the inlet end of the stand pipe 20 is somewhat below the water level of the water contained in the wheel pit or well formed above the bottom 3 and the wheel pit 6, so that a fresh supply of comparatively clean water is continuously discharged upon the articles to be cleaned, the scum, grease and the like remaining on the water level.

By the provision of the laterally shaped deflector 37, the heavier particles which settle by gravity are directed into the bottom of the wheel pit and can be readily withdrawn through the valve pipe, 7, according to requirements.

It will be seen from the foregoing that only a small amount of power is required for forcing the water through the stand pipe 20, by means of the propeller wheel or wheels, which are directly connected by their shaft to the motor drive, which is suitably packed to prevent leakage. By the provision of the vertical stand pipe having slots cut in it on levels suited to the racks, screens or baskets which carry the dishes which are on an angle, a continuous stream of water is forcibly directed in all directions directly upon the surface of the dishes placed on the racks.

The revoluble sprayer or spreader at the top of the stand pipe having the plurality of pockets on its bottom surface arrests the water in its course upwardly and overflow-

ing at the top and impinging against said pockets causes said sprayer rapidly to rotate and as there are varying degrees of openings in the periphery of said sprayer, the direction of the water is changed or altered from right angles in the stand pipe down to the angle of 35°, so that I get a wide distribution of the water up and down the sides of the tank thus creating an effective scouring action, due to the different angles of the water, as well as the rotating effect given to the water by means of said sprayer. This action is most efficient in instantly cleansing the surface of the dishes to be cleaned.

Attention is also called to the fact, that the machine is rapidly taken apart for the purpose of cleaning, inspection or repair, and it is readily accessible at all times for this purpose.

Another highly important feature in this machine is the fact that once the grease and foreign matter adhering to the dishes are removed, the grease being lighter than water, floats on the surface of the same and as the bottom end of the stand pipe extends below this surface, the action of the water propelled device is to force upwardly the clean water beneath the surface or water level and throw it over the dishes, so that I do not throw the accumulation of what has been taken from the surface of the dishes and deposit it back again on them during the operation of cleaning.

By the provision of the wheel pit member 6 in the bottom of the tank, a well is formed so that I get a solid and constant volume of water supply at all times, and the umbrella shaped deflector 37 having the space 38 beneath it forms a sediment pocket, where the heavier particles of foreign matter will settle, which are readily drawn off by means of the discharge pipe 7, thus further insuring cleaner water for the dish washing operation.

It will now be apparent that I have devised a novel and useful construction of a dish washer, which embodies the features of advantage enumerated as desirable in the statement of the invention and the above description, and while I have in the present instance, shown and described preferred embodiments thereof which will give in practice satisfactory and reliable results, it is to be understood that the same is susceptible of modification in various particulars without departing from the spirit or scope of the invention or sacrificing any of its advantages. It will now be apparent that I have devised a novel and useful construction of a dish washer which embodies the features of advantage enumerated as desirable in the statement of the invention and the above description, and while I have, in the present instance, shown and described embodiments thereof which will give in practice satis-

factory and reliable results, it is to be understood that such embodiments are susceptible of modification in various particulars without departing from the spirit or scope 5 of the invention or sacrificing any of its advantages.

Having thus described my invention, what I claim as new and desire to secure by Letters Patent, is:—

- 10 1. In a machine of the character stated, a casing, a stand pipe therein, water propelling devices at the bottom of said stand pipe, and a water sprayer and spreader, rotatably mounted above the top of said stand pipe and adapted to deflect laterally and downwardly in different planes, the water impinging thereon from said stand pipe.
- 15 2. In a machine of the character stated, a casing, a stand pipe therein, having ports in its upper and intermediate portions, water propelling devices at the bottom of said stand pipe, and a water sprayer and spreader rotatably mounted at the upper portion of said stand pipe and provided 25 with a plurality of pockets on its under side adapted to deflect the water impinging thereon from said stand pipe laterally and downwardly in a plurality of directions.
- 30 3. In a machine of the character stated, a casing, a stand pipe therein, having ports in its upper and intermediate portions, water propelling devices at the bottom of said stand pipe, a revoluble water sprayer and spreader mounted at the upper portion of 35 said stand pipe and provided with a plurality of pockets on its under side each of

different depth and contour and adapted to deflect the water impinging thereon from said stand pipe laterally and downwardly in a plurality of directions, and supporting 40 devices for the articles to be washed, located in proximity to said ports.

4. In a machine of the character stated, a casing, a wheel pit in the lower portion thereof, a stand pipe supported above said wheel pit, water propelling devices in the bottom of said stand pipe, the inlet to the latter being below the water level, and a rotary water sprayer and spreader mounted on the top of said stand pipe and provided 45 with a plurality of pockets, each of the latter being of different depth and contour for deflecting the water in a plurality of directions.

5. In a machine of the character stated, a casing, a wheel pit in the lower portion thereof, a stand pipe supported above said wheel pit, water propelling devices in the bottom of said stand pipe, the inlet to the latter being below the water level, a rotary 50 sprayer and spreader mounted on the top of said standpipe and provided with a plurality of pockets for deflecting the water in a plurality of directions, a vertical driving shaft mounted in the bottom of said wheel pit, and a deflector below said propelling devices for deflecting the heavier particles to the bottom of said wheel pit.

HOWE E. DANTZEBECHER.
